ATTORNEY.

UNITED STATES PATENT OFFICE.

GEORGE A. DRIGGS, OF WATERBURY, CONNECTICUT.

DESIGN FOR A DISPLAY-STAND.

SPECIFICATION forming part of Design No. 23,735, dated October 23, 1894.

Application filed September 17, 1894. Serial No. 523,280. Term of patent 14 years.

To all whom it may concern:

Be it known that I, GEORGE A. DRIGGS, a citizen of the United States, residing at Waterbury, in the county of New Haven, State of Connecticut, have invented and produced a new and original Design for a Display-Stand, of which the following is a specification.

The accompanying drawing is a perspective side elevation of a display stand containing the leading features of my new and original design.

The principal feature consists in an upright column A diverging at the base, and supporting at intervals and horizontally, a series of cup-shaped trays or receptacles B B

the said upright column being represented as passing through the center of said trays. Each tray is graduated in size so that when mounted on the column A, the smaller ones above the larger ones as shown, the effect produced to the eye is that of a tapering or conical column.

What I claim is—

The design for a display stand herein shown and described.

GEORGE A. DRIGGS.
